UNITED STATES PATENT OFFICE.

EMERSON R. NEWELL, OF NEW YORK, N. Y., ASSIGNOR TO ELEVATOR SUPPLY & REPAIR COMPANY, OF CHICAGO, ILLINOIS, A CORPORATION OF ILLINOIS.

ELEVATOR SIGNALING APPARATUS.

1,160,315.

Specification of Letters Patent.

Patented Nov. 16, 1915.

Application filed June 6, 1908. Serial No. 437,050.

To all whom it may concern:

Be it known that I, EMERSON R. NEWELL, a citizen of the United States, residing at New York city, New York, have invented 5 certain new and useful Improvements in Elevator Signaling Apparatus, of which the following is a clear, full, and exact description.

My invention relates to an elevator signaling apparatus in which a signal or signaling means is provided which is adapted to give a signal to either the operator of the car or the intending passenger, and to restore the same and the circuits which operate 15 such signaling means to normal condition, and which shall be controlled (preferably at the several floors) by the operator of the car, preferably through operation of the gate mechanism, and my object is to provide 20 a construction which shall be simpler and less expensive to install than the mechanisms hereofore used.

Prior devices which have been used have restored the signal circuits to normal condition solely by the operation of the doors or gates at the several floors, such, for example, as the two McLean Patents #748,408 and 25 748,409, and I believe that I am aware of all such mechanisms as have been in use or 30 patented, but in most, if not all, of those in which the circuits are restored to normal condition merely by the floor gates or doors, it has been necessary to run at least one wire down the hatchway to each door. Thus in, 35 for example, a twenty-story building, to run at least twenty wires down the hatchway to the several gates. This makes an expensive and objectionable construction, for the cost of installation in an elevator 40 signaling apparatus is a very material factor in the ultimate cost to the owner of the building. It is sometimes desirable to accomplish the restoring to normal condition of the circuits by the floor gates, instead of 45 solely by the commutator which is moved correspondingly with the movement of the car, because in the latter case if one car of a bank of elevators is full of passengers and cannot stop at a floor from which a signal 50 has been given, the elevator operator must press a so-called "transfer button" in the car in order to pass that floor and still leave the circuits and mechanism in condition such

that the next following car will receive the signal and stop and pick up the passenger, 55 but where the mechanism is such (as in said McLean patents) that the circuits are not restored to normal condition unless a floor gate is opened, the operator, if his car is full, may run on down, or pass the floor, and 60 still leave the circuits or mechanism in condition such that the next following car will receive the signal.

I am aware that my invention may be embodied in widely differing forms, but in the 65 drawings I have shown a preferred embodiment of my invention which is applicable to an elevator signaling apparatus now widely in use and which is described in the Smalley & Reiners Patent #826,752, dated July 24, 70 1906.

In the drawings, Figure 1 represents a diagram of two shafts and floors with two commutators and mechanism such as illustrated in said Smalley & Reiners patent, 75 with my invention substituted therein; Fig. 2 represents merely the restoring circuits; Fig. 3 a diagrammatic view of a still more simplified circuit; and Fig. 4 shows a modified form of the invention (mostly diagrammatic), and Figs. 5 and 6 are detail views of a portion of the same.

Referring to Fig. 1 of the drawings, the third and fourth floors of a building are shown with two cars A and B moving in 85 their respective shafts, and passing the doors or gates 1, 2, 3 and 4 located at said floors by which the intending passengers are admitted to the cars. 5, 6 and 7, 8, are up and down passenger's buttons at each floor, which 90 are devices to be operated by the intending passengers when they wish to take passage in the car, and which are preferably the ordinary normally-open push-button switches commonly used in such installations. 95

In the embodiment shown in the drawings, I have provided electrically-operated signaling means for signaling to the operator of the car to stop at the floor where the push-button has been pushed, and also separate 100 signaling means located at each floor for signaling to the intending passenger which car is closest to him and moving in the direction he has signaled he wishes to go. These signals are, preferably, a single signal lamp 9 or 10 in each car for signaling 105

to the operator, and up and down stationary signal lights outside of each shaft, such stationary signals being shown at 11 to 18 in pairs over the doorway outside of each shaft. It will be evident that either one of these two signaling means may be omitted without varying the operation of the remainder of the device, and obviously they may be of widely differing constructions as will be evident to any one skilled in the art, as the main purpose of a signal means within a car is to signal the operator to stop at a floor, and the signaling means for the intending passenger is to tell him which car will take him aboard. It is also common in the art to use a series of signals in the car, one for each floor, as shown, for example, in Patent 634,229. The signals shown in the drawings are, preferably, operable only when a car is approaching the floor, but it may not be desirable in all cases to have a signal in the car given only when the car approaches the floor at which the push-button has been pushed.

In order to determine the time when a signal can be given, one of the floor push-buttons must be pushed, and if it is desired to have a signal given only when a car approaches a floor (which is the preferable construction), a so-called "commutator" is used which, or a portion of which, is moved by suitable connection to the hoisting mechanism of the elevator, and therefore moved correspondingly with, but usually much slower than, the elevator and which renders a signal inoperative except when a car is approaching the floor on which a push-button has been operated and is moving in the direction indicated by such push-button. The stationary portion of such commutator for car B is indicated generally by C, and by D for car A. The moving portions are represented by F and H.

The means for determining the time when a signal can be given also comprises signal controller mechanism corresponding to each floor which is represented as a whole by S. I prefer to provide only two of these signal controllers for each floor one for the "up" direction and the other for the "down" direction, for the entire bank of elevators, instead of providing a separate one, or a separate pair, for each elevator. One such signal controller is illustrated, for example, by a mercury pot 19 and switch arm 20, which latter may be dropped into the pot whenever a push-button is pushed. In the construction illustrated in the drawings, this controller 19, 20, is, as hereafter explained, common to both the elevators, as it is cross-connected to the two commutators. The switch arm is pivoted and normally held in its raised position by a pivoted detent 21, which normally stands in the position in which detent 22 is shown. 23 is a setting magnet.

When the push-button 8 is operated, it will close a circuit from, for example, the battery 24, through said push-button and magnet, and energize the latter, thereby drawing detent 21 out of engagement with the arm 20 and allowing it to fall into the mercury pot. The signal controller 19, 20 controls all the signals with reference to the fourth floor when the car is moving upwardly, because it controls the "up" signals 14 and 18, and also controls the signal within the car with reference to the fourth floor, because it will render said signals operative when the moving portion of the commutator arrives at its proper position, as hereafter explained. 25, 26 is a "down" signal controller corresponding to said floor, and also set by its corresponding "down" push-button 7 and which controls the "down" signals 13 and 17, and also the car signals when the cars are moving downwardly and approaching said fourth floor. 27, 28 and 29, 30 are up and down signal controllers for the third floor, which are similar in construction to the ones just described.

Referring to the specific mechanism shown in the drawings, each floor is represented by one or more relatively stationary contact plates for each direction of movement of the car, for it will be observed that the "down" lamp 11 on the third floor is connected to the contact plate 31, and the "up" lamp 12, to 32, and the up and down lamps 14 and 13 on the fourth floor are connected to the plates 34 and 33. Similarly, also, the up and down lamps 15 to 18 for car A are each connected to separate contact plates 35 to 38, and it will be obvious that each one of these plates represents its own particular light or signal. I also preferably provide another lot of plates corresponding to the ones just mentioned and indicated by 39 to 46, inclusive, which are connected to their respective mercury pots in parallel. For example, the "up" plates 39 and 45 are connected together and to the mercury pot 19, so that if arm 20 is in the mercury pot 19 the "up" lamp 14 will be lighted whenever a connection is made from plate 39 to plate 34. It will be observed that there are normally two breaks in the circuit to this floor light 14, one at the mercury pot and the other between the plates 39, 34, and this is the preferable construction, although it is not necessary in all cases.

The moving portion of the commutator for car B is indicated by F, in which the dotted rectangular figure represents a carriage for supporting and moving the brushes of the commutator across the relatively stationary contact plates. 47 represents a series of brushes which, when the car is moving up, will bridge the plates 34, 39, etc., and 48, represents two pairs of brushes, which

will bridge the plates 39, 40 and the long contact strip 49. As the car B moves upwardly, the brushes will move upwardly over the contact plates and bridge the breaks 5 between 32 and 40, and then between 40 and 49. The upper pair of brushes 47 will strike the plates 34, 39 when the car reaches about the second floor, and will then close a circuit through the "up" lamp 14 to plate 34, 10 by the brush to plate 39, to the mercury pot 19, and back to the dynamo 49 or other source of supply, thus lighting up the "up" lamp, which will remain lighted because of the series of brushes 47 until the car reaches 15 the fourth floor.

The signal 9 within the car is also controlled by the two pairs of brushes 48, the upper pair of which will bridge the break between the plate 39, and the strip 49 when 20 the car reaches about the third floor, for they will close a circuit from the dynamo 49, through the car lamp, and by the wire 50 to strip 49, to plate 39, and back to the "up" 25 fourth floor controller 19, 20, thus lighting up the signal in the car when the car is approaching the floor on which the "up" push-button has been pushed, and it will be observed that the car signal will, in the embodiment shown in the drawings, be lit up 30 (like the outside floor lamps) only when the car is approaching the floor.

In order to put the commutator in condition to operate only the "up" signal lights outside the shaft and the car light 35 when an "up" push-button has been pushed (so long as the car is moving upwardly), and to prevent the giving of a "down" signal, (and vice versa when the car is moving downwardly) it is common in the art to provide 40 a construction with mechanism which will accomplish this result. In the before-mentioned Smalley & Reiners patent 826,752, the brushes are automatically shifted, when the car reverses its direction of movement, 45 so as to shift the same from the operative position shown at F in Fig. 1, to the position shown at H, that is, when the car reaches the top of the shaft and starts to move down, the brushes 47 are shifted so 50 that they would not bridge between plates 34 and 39, but would travel over merely plates 39 and 40, and brushes 48 so that they travel upon only the strip 49, and the restoring brushes 51 rest upon only strip 52, 55 thus putting them practically out of operation. Brushes 53 for controlling the "down" floor lights, as well as the car light brushes 54, and the "down" restoring brushes 55 are shown in their inoperative 60 position, and when the car starts to move down, they are shifted across to the same relative position as shown by the brushes 53', 54' and 56 of the moving portion H of the commutator at the left. I do not consider it necessary to show the mechanism for

shifting such brushes, as it will be evident to any one skilled in the art that it can be accomplished in a variety of ways. Thus it will be seen that when a car is moving upwardly, for example, neither the outside 70 floor lights, nor the light within the car, will be lit up, except in response to the operation of an "up" push-button, and no signal will be given if a "down" push-button is operated. 75

In order to restore the circuits and the signals to normal condition after a signal has been given, I have provided a restoring mechanism which is normally inoperative to accomplish such restoring, but which is 80 made operative for this purpose at certain times and which comprises a selecting device which is moved correspondingly with the car and which, when made operative, will select (because it moves correspondingly with the car) the proper signal controller which is to be restored, and I render the restoring mechanism operative by a switch device (preferably at each floor) which is under the control of or operable by 85 the operator of the car, preferably through the operation of the several door mechanisms at the floors, such as by opening any door for the admission of the passenger. In the embodiment shown in the drawings, stationary contact plates 58, 59 are provided, which correspond to the third and fourth floors, and the pair of brushes 51 are in such position that they successively bridge the breaks between the strip 52 and said contact 90 plates just as the car starts to leave the corresponding floors. For example, when the car is at the fourth floor and starts to move up from it, the brushes will be in the position shown at the right of Fig. 2, that is, 95 in such a position that they rest upon contact plate 59. When the brushes so bridge strip 52 and plate 59, a circuit would be closed from strip 52, through brush 51 and by wire 57', to and through the up restoring magnet 158 of the "up" fourth floor controller 19, 20, and back by wire 59' to the battery, but it will be observed that said circuit is now open at each floor at points 100 60, 61. Down each hatchway or shaft are run two wires, 62 being a common feed wire 105 from the battery, and 63 the return, which is connected to the feed strips 52 and 64. If any of the switches 60, 61 are closed when the brush 51 bridges the break between strip 110 52 and contact 59, the restoring magnet 158 will be energized. As, however, there is a restoring contact (such as 59) corresponding to each floor, and as the brush 51 rests on such contact only when the car is at the 115 corresponding floor, and as the elevator operator can obviously only open the door of the floor at which the car then is, only the corresponding signal controller will be restored to normal condition. 120

125

130

135

Fig. 2 shows the restoring circuits of Fig. 1 without the remaining portions of said latter figure. Assuming that the car B has just reached the fourth floor and is moving upwardly, the brush 51 is then bridging the break between 59 and 52. When the operator opens the door 4 in the direction of the arrow, the stop 65 will strike the switch 60 and close it, thus closing a circuit 10 through the restoring magnet 158, which will draw the switch arm 20 out of the mercury pot and restore it to normal condition, and it will be obvious that at whatever floor the operator stops, he will restore the corresponding controller, providing that said controller has been set and corresponds to the direction in which the car is moving. The contact plates 58, 59 are for the "up" direction of movement of the car. The corresponding contacts 66, 67 and the brush 55 are for the "down" direction of movement of the car, and with the parts in the position shown in the upper right-hand corner of Fig. 1, or at the right of Fig. 2, opening a 20 door will not restore any of the "down" signal controllers such, for instance, as 30, 29, because the brush 55 is then in position such that it travels over only strip 64.

The commutator at the left of Figs. 1 and 30 2 is shown in the position in which the car is traveling down. The "down" push-button 5 on the third floor has been pushed and has closed a circuit through the "down" setting magnet 69, and has dropped the controller arm 30 into the mercury pot 29. When the brushes 53' bridge the contacts 35, 44, a circuit will be closed through the "down" light 15, and when the brushes 54' bridge across from strip 70 to contact 44, 40 a circuit will be closed through the signal 10 in car A. When car A stops at the third floor going down, brush 56 will be in the position shown in Fig. 2, and if the elevator operator opens door 1, it will close a circuit 45 through the "down" restoring magnet 71, thus restoring the controller 30, 29 to normal condition.

In Fig. 3 I have shown an electrical diagram of the restoring circuits showing 50 merely the "up" restoring contacts 58, 59, and brush 51 for car B and the "up" restoring contacts 75, 76 and brush 77 for car A. In this figure it is assumed that both cars are moved upwardly, that car B has 55 just reached the fourth floor, and that car A is just approaching the second floor. The brushes are moving in the direction of the arrow of Fig. 3. When the operator of car B opens his door, he will close the switch 60, thus energizing restoring magnet 158, and when car A reaches the third floor (moving upwardly), brush 77 would be on contact 75, and if he opens the third floor door he would close the switch 79, thus 65 energizing up restoring magnet 80.

It will be seen that the door switches 60, 61 are connected across the restoring circuit in parallel, and therefore it is only necessary to run two wires down each hatchway or shaft, because the single restoring circuit 70 for the shaft at the right is controlled in its time of operation by the selective device consisting of the moving brush 51, with the series of restoring contact plates. This is much simpler and much less expensive to 75 install than constructions such as used heretofore in which a separate wire, or possibly two or more wires, had to be run down the shaft to each doorway. As the restoring circuits are open at all times until a door 80 switch is operated, the restoring mechanism, is therefore normally inoperative, or unable to automatically restore the signal controllers to normal condition, but the same can be rendered operative to restore the signal controllers by the operation of the door mechanism, and the movable restoring brushes select which signal controller shall be restored. As the commutators in Fig. 1 are the same as in said Smalley & Reiners 90 patent, this invention may be used with such form of commutator without any change whatever, as it is only necessary to connect the normally open restoring circuit to the corresponding restoring feed strips, as 95 shown in the drawings.

The electrically-operated signaling means adapted to give a signal whenever a car approaches a floor may, it will be observed, be considered to refer to a series of signals, or 100 a single signal, because the series of "up" lights 12, 14, for example, for signaling to the intending passenger, are such, as is also the single signal 9 within the car. The electrically-operated signal for a shaft and car 105 may also refer to either the signal within the car for signaling to the operator, or one of the lights outside the shaft for signaling to the intending passenger. The gate mechanism for operating the restoring floor 110 switches, such as 60, 61, may obviously be of widely varying constructions, for it will be obvious that any mechanism which is operated by the operator when he stops at a floor and admits the passenger and which 115 would close the circuit, would accomplish some of the advantageous results of the mechanism shown as the preferred embodiment of my invention, but I prefer to have the floor switches closed by the door mechanism when the door is opened, because it will be observed that when the door is opened to admit the passenger the switch 60, for example, will be practically instantaneously closed and opened again, and if 120 the door is left open to its full extent and the car remains at the floor, the restoring circuit will not be closed except for an instant. The same thing will occur when the door is shut again. 125 130

In Figs. 4, 5 and 6 I have shown a construction to accomplish the same general results, but in which the signal controllers corresponding to each floor, which are set by the operation of the corresponding push-buttons, are of a different construction. In such alternative construction each floor is represented by two long bars, one for "up" and one "down." One such bar 90 is indicated in Fig. 5. It is normally held slightly to the left against the tension of spring 91, by means of a detent 92. When a push-button is pushed, it energizes said magnet 93, withdraws the detent and allows the spring 91 to pull the bar a quarter of an inch or so to the right, to the position shown, where it rests against the stop 94. The bar carries a block 95 containing a spring-pressed plunger 96 and an insulated contact 97. The bar in Fig. 5 is shown turned over ninety degrees from that in Fig. 4, as Fig. 4 represents a plan view. Bar 90 is the "up" bar for the third floor, and in the drawings the "up" push-button 98 is assumed to have been pushed. Bars 101 and 102 representing the "up" and "down" bars, respectively, for the fourth floor are in their normal position, but "up" and "down" bars 90 and 100 for the third floor are shown as having been released by the "up" and "down" push-buttons 98 and 99. A commutator device moving correspondingly with the movement of the car is also provided, consisting of a mechanism carried on a moving block 103 (Fig. 6) which carries on it the two cam portions 104 and 105, which press in the respective plungers at the proper times so as to light up the lights in substantially the same manner as the moving portions of the commutator in the other construction. It will be observed that each floor light is connected to a contact such as 97. As the cam 104, for example, moved upwardly, it would strike plunger 96 and move it just sufficiently to touch spring 97, thus closing the circuit through the "up" light 16 for the third floor. The links 106, 107, together with the slotted ends 108, 109 of the cams 104 and 105 are moved as the car reverses its direction of movement to throw the proper cam into operative position, and the other cam out of operative position. Assuming the car at the left to be moving upwardly, the link 106 has thrown the cam 104 to its position shown, such that it will contact with the plunger 96 but will just escape the corresponding "up" plunger 111 of the "up" bar 101 for the fourth floor, (the "up" push-button on the fourth floor not having yet been pushed). The link 107 has thrown the cam 105 to its inoperative position so that it would not contact with plungers 112 or 113 even if both bars 100 and 102 were released. It will therefore be observed that

when a push-button is pushed it will release a bar, and when the cam corresponding to that direction of movement approaches, it will press in the corresponding plunger of that bar and light the corresponding light. 70
In order to restore the bars to normal condition, I have provided upon the same block which carries the cams, another cam or cams which operates upon the respective bars. In Figs. 4 and 6, 114 is a cam carried on the far side of the block 103 and which is rocked by means of a rocking rod 115 which passes through a slot 116 shown in dotted lines in Fig. 4. This rod and cam is rocked at the proper times by means of a toggle 117 actuated by means of a magnet 118. On the bar 90 is a projection 119 in line with the cam and which will be engaged by it so as to move the bar back to the position where it is engaged by the detent. The cam normally stands in the broken position of the toggle, such as shown by the cam 120 at the right of Fig. 4. The same normally-open restoring circuit as in Figs. 1, 2 and 3 is provided, the return wire 63 of which is connected to magnet 118 when the car is moving up, for example. When the cam 114 and its toggle 117 are in the normal position (that is, in the position of cam 120 and its toggle), the opening of door 1, for example, will close the circuit through the magnet and draw down the core 122, cause the upper end of the slot 123 to strike pin 124 and throw the toggle down to the position shown at the left of the figure. When the car is standing at the third floor, the cam is in such a position that the cam 114 is about to engage the stop 119, and as the car moves up the cam will move the bar back to normal position and the spring 125 will move the plunger out of engagement with spring 97. The cam will engage the block about at the point indicated by the dotted line at the right of the pivot 127, and will move down the face of the cam 114 until the detent again engages the lug 128, which will occur just before 119 passes to the left of the pivot 127. As 119 passes onto the left end of the cam beyond the pivot, it will cause the toggle to break and the same will be thrown up into its broken position, which will draw the cam back to the position indicated in dotted lines at 129, that is, to such a position that it will just escape contact with any other "up" bar 120 (such as block 130 of bar 101) even if the same had been released. The cam is therefore normally inoperative to restore the bars to normal condition, but is rendered operative by the opening of a floor gate. 125

In order to operate the other cam 131 for restoring the "down" bars, a similar magnet 132 is provided, together with a switch 133 which is automatically thrown from the position shown to a position such that the 134

return wire 63 is connected with the wire 134 when the car reaches the top of the shaft and reverses its direction of movement. When the car starts down, the cam 104 and 5 the magnet 118 with its cam will be out of operative relation, and, conversely, the cam 105 with its magnet 132 and toggle cam 131 will be in condition to give the "down" signals and restore the "down" bars. The car 10 for the shaft at the right is also provided with similar signal-controlling cams 136, 137 and restoring cams 120, 137', magnets 138, 139 and switch 140. It will be obvious 15 that the operation of this construction is substantially the same as in the construction illustrated in Figs. 1, 2 and 3. The construction at the right of Fig. 4 is assumed to be in the position in which the car is moving downwardly, one of the gates having been 20 opened to throw the cam 137' to its present position.

It will be obvious that my invention is applicable to other forms of apparatus than herein illustrated, as the same may be widely 25 varied, and I therefore do not confine myself to the construction illustrated.

What I claim is:—

1. In an elevator signaling apparatus in combination, an electrically-operated signal, 30 means for determining the time when said signal can be given comprising a passenger's button at the floor and a signal controller mechanism corresponding to said floor set through operation of said button, 35 restoring mechanism to automatically restore said signal controller to normal condition and comprising a selecting device moved correspondingly with said car throughout the greater portion of the travel 40 of said car, gate mechanism at each floor for admission to the car and means controlled by said gate mechanism rendering said selecting device operative to restore said controller only when a gate mechanism 45 is operated.

2. In an elevator signaling apparatus in combination, an electrically-operated signal carried by a car, means for determining the time when said signal can be given comprising 50 a passenger's button at the floor and a signal controller mechanism corresponding to said floor set through operation of said button, restoring mechanism to automatically restore said signal controller to normal condition and comprising a selecting device moved correspondingly with said car throughout the greater portion of the travel 55 of said car, gate mechanism at each floor for admission to the car and means controlled by said gate mechanism rendering said selecting device operative to restore said controller only when a gate mechanism is operated.

3. In an elevator signaling apparatus in 65 combination, an electrically-operated signal

carried by a car, means for determining the time when said signal can be given and comprising a passenger's button at each floor and signal controlling mechanism corresponding to each floor and set through operation of their corresponding buttons, restoring mechanism comprising a selecting device moved correspondingly with said car and adapted to restore said controllers to normal condition in succession, gate mechanism at each floor for admission to the car, and means controlled by said gate mechanism rendering said selecting device operative to restore a controller only when a gate mechanism is operated. 75

4. In an elevator signaling apparatus in combination, an electrically-operated signal, means for determining the time when said signal can be given and comprising a passenger's button at each floor and a commutator operated by the car and signal controller mechanism corresponding to each floor set through operation of their corresponding buttons, restoring mechanism comprising a selecting device moved correspondingly with said car and adapted to restore said controllers to normal condition in succession, gate mechanism corresponding to each floor for admission to the car and means controlled by said gate mechanism rendering said selecting device operative to restore a controller only when a gate mechanism is operated. 85

5. In an elevator signaling apparatus in combination, an electrically-operated signal carried by a car and a stationary one at a floor, means for determining the time when said signals can be given, and comprising an up and down passenger's button at each floor and a commutator operated by the car and up and down signal controller mechanism corresponding to each floor set through operation of their corresponding buttons, restoring mechanism comprising up and down selecting devices moved correspondingly with said car, and adapted to restore said controllers to normal condition in succession, gate mechanism at each floor for admission to the car, and means controlled by said gate mechanism rendering one of said selecting devices operative to restore a controller only when a gate mechanism is operated, and means rendering the down selecting device inoperative when the car is moving upwardly. 100

6. In an elevator signaling apparatus in combination, an electrically-operated signal, means for determining the time when said signal can be given comprising a passenger's button at the floor and a signal controller mechanism corresponding to said floor set through operation of said button, restoring mechanism to automatically restore said signal controller to normal condition and comprising a selecting device moved correspond- 105

ingly with said car throughout the greater portion of the travel of said car, gate mechanism at each floor for admission to the car and means controlled by said gate mechanism

5 nism rendering said selecting device operative to restore said controller only when a gate mechanism is operated and comprising a normally-open switch at each floor closed by its corresponding gate mechanism when 10 operated, said switches being connected in parallel.

7. In an elevator signaling apparatus in combination, a plurality of shafts and cars, electrically-operated signals corresponding 15 to the cars, means for determining the time when said signals can be given and comprising a passenger's button at each floor and signal controllers for each floor common to all said cars and adapted to be set 20 through the operation of their corresponding buttons, restoring mechanism comprising a selecting device for each car moved correspondingly to its car and adapted to restore said controllers to normal condition 25 in succession, gate mechanism at each floor and shaft for admission to the cars, and means controlled by said gate mechanism rendering said selecting devices operative to restore said signal controllers only when a 30 gate mechanism is operated.

8. In an elevator signaling apparatus in combination, a plurality of shafts and cars, electrically-operated signals carried by the cars, means for determining the time when 35 said signals can be given and comprising a passenger's button at each floor and signal controllers for each floor common to all said cars and adapted to be set through the operation of their corresponding buttons, re- 40 storing mechanism comprising a selecting device for each car moved correspondingly to its car and adapted to restore said controllers to normal condition in succession, gate mechanism at each floor and shaft for 45 admission to the cars, and means controlled by said gate mechanism rendering said selecting devices operative to restore said signal controllers only when a gate mechanism is operated.

50 9. In an elevator signaling apparatus in combination, a plurality of shafts and cars, electrically - operated signals corresponding to the cars, means for determining the time when said signals can be given and 55 comprising a passenger's button at each floor and signal controllers for each floor common to all said cars and adapted to be set through the operation of their corresponding buttons, restoring mechanism comprising a 60 normally inoperative selecting device for each car moved correspondingly to its car and adapted to restore said controllers to normal condition in succession, gate mechanism at each floor and shaft for admission 65 to the cars, and means controlled by each

gate mechanism rendering the corresponding selecting device operative to restore only the controller of the floor at which said gate is located.

10. In an elevator signaling apparatus in 70 combination, electrically-operated signal means adapted to give a signal whenever a car approaches a floor, means for determining the time when a signal shall be given and comprising a passenger's button at each 75 floor and a signal controller corresponding to each floor set through operation of its corresponding button and a commutator operated correspondingly with said car and adapted to prevent the giving of a signal 80 except when said car is approaching the floor on which a passenger's button has been operated, normally inoperative restoring mechanism to restore said signaling means to normal condition and comprising a rela- 85 tively stationary device corresponding to each floor and a selecting device movable correspondingly to said car and adapted to coöperate with said stationary devices in 90 succession, gate mechanism at each floor for admission to the car, and means controlled by each of said gate mechanisms when operated and adapted to render said restoring mechanism operative to restore to 95 normal condition the signal which has been given.

11. In an elevator signaling apparatus in combination, a shaft and car, an electrically-operated signal, means for determining the time when such signal can be given 100 and comprising a passenger's button at a floor and a signal controller corresponding to said floor set through operation of said button, normally inoperative restoring mechanism to automatically restore said 105 signal controller to normal condition and comprising a selecting device moved corre- 110 spondingly with said car throughout the greater portion of the travel of said car, a normally-open electric circuit which, when closed, renders said restoring mechanism operative, gate mechanism at said floor for admission to the car and a switch operated by said gate mechanism to close said circuit.

115 12. In an elevator signaling apparatus in combination, a shaft and car, an electrically-operated signal, means for determining the time when such signal can be given and comprising a passenger's button at each 120 floor and signal controller mechanism corre- 125 sponding to each floor set through operation of their corresponding buttons, normally inoperative restoring mechanism comprising a selecting device moved correspondingly with said car and adapted to restore said controllers to normal condition in succession, a normally-open electric circuit which, when closed, renders said restoring mechanism operative, gate mechanism at each floor for admission to the car, and a switch for each 130

- gate operated by its gate mechanism to close said circuit, said switches being connected in parallel.
13. In an elevator signaling apparatus in combination, a shaft and car, an electrically-operated signal, means for determining the time when such signal can be given and comprising a passenger's button at each floor and signal controller mechanism corresponding to each floor set through operation of their corresponding buttons, normally inoperative restoring mechanism comprising a selecting device moved correspondingly with said car and adapted to restore said controllers to normal condition in succession, a normally-open electric circuit which, when closed, renders said restoring mechanism operative, and a switch in said circuit at each floor and operable by the operator of the car for closing said circuit.
14. In an elevator signaling apparatus in combination, a car, electrically-operated signaling means, means for operating the same comprising a passenger's-button at each floor and mechanism corresponding to each button and set thereby, restoring mechanism comprising a selecting device moved correspondingly with the car whereby the restoring mechanism is adapted to restore all said passenger's-button-set mechanisms in succession and correspondingly with the movement of the car, said restoring mechanism being normally incapable of accomplishing the restoration, and means operable by the operator in the car and adapted, when operated, to put said restoring mechanism in condition such that the selecting device will accomplish the restoration.
15. In an elevator signaling apparatus in combination, a car, electrically-operated signaling means, means for operating the same comprising a passenger's-button at each floor and mechanism corresponding to each button and set thereby, restoring mechanism comprising a selecting device moved correspondingly with the car whereby the restoring mechanism is adapted to restore all said passenger's-button-set mechanisms in succession and correspondingly with the movement of the car, said restoring mechanism being normally incapable of accomplishing the restoration, a switch normally held open but closable by the operator in the car and adapted, when closed, to put said restoring mechanism in condition such that the selecting device will accomplish the restoration.
16. In an elevator signaling apparatus in combination, a car, electrically-operated signaling means, means for operating the same comprising a passenger's-button at each floor and mechanism corresponding to each button and set thereby, restoring mechanism comprising a selecting device moved correspondingly with the car whereby the re-
- storing mechanism is adapted to restore all said passenger's-button-set mechanisms in succession and correspondingly with the movement of the car, said restoring mechanism being normally incapable of accomplishing the restoration, a gate at each floor, and means comprising a normally-open switch for each gate closed and opened when its gate is moved, each switch being adapted, when operated, to put said restoring mechanism in condition such that the selecting device will accomplish the restoration.
17. In an elevator signaling apparatus in combination, a pair of cars, electrically-operated signaling means corresponding to each car, means for operating the same comprising a passenger's-button at each floor and mechanism corresponding to each button and set thereby, restoring mechanism comprising a selecting device for each car moved correspondingly with that car whereby each selecting device is adapted to restore all said passenger's-button-set mechanisms in succession and correspondingly with the movement of its car, said restoring mechanism being normally incapable of accomplishing the restoration, a switch corresponding to each floor for each car and operable by the operators in the cars, each switch being adapted, when operated, to put the restoring mechanism in condition such that the selecting device of the corresponding car will accomplish the restoration.
18. In an elevator signaling apparatus in combination, a pair of cars, electrically-operated signaling means corresponding to each car, means for operating the same comprising a passenger's-button at each floor and mechanism corresponding to each button and set thereby, restoring mechanism comprising a selecting device for each car moved correspondingly with that car whereby each selecting device is adapted to restore all said passenger's-buttons-set mechanisms in succession and correspondingly with the movement of its car, said restoring mechanism being normally incapable of accomplishing the restoration, a gate at each floor for each car, and a normally-open switch for each gate closed and opened when its gate is moved, each switch being adapted, when operated, to put the restoring mechanism in condition such that the selecting device of the corresponding car will accomplish the restoration.
19. In an elevator signaling apparatus in combination, a pair of cars, electrically-operated signaling means corresponding to each car, means for operating the same comprising an up and a down passenger's-button at each floor and mechanism corresponding to each button and set thereby, restoring mechanism comprising a selecting mechanism for each car moved correspondingly

with that car whereby each selecting mechanism is adapted to restore, in succession, and correspondingly with the movement of its car, those passenger's-button-set mechanisms 5 which correspond to the direction the car is moving, said restoring mechanism being normally incapable of accomplishing the restoration, a gate at each floor for each car, and a single normally-open switch for each gate 10 closed and opened when its gate is moved, each switch being adapted, when closed, and irrespective of the direction said car is moving, to put the restoring mechanism in condition such that the selecting mechanism of 15 the corresponding car will accomplish the restoration.

20. In an elevator signaling apparatus in combination, a pair of cars, electrically-operated signaling means carried by each car, means for operating the same comprising a passenger's-button at each floor and mechanism corresponding to each button and set thereby, restoring mechanism comprising a selecting device for each car moved 25 correspondingly with that car, whereby each selecting device is adapted to restore all said passenger's-button-set mechanisms in succession and correspondingly with the movement of its car, said restoring mechanism 30 being normally incapable of accomplishing restoration, means for each car operable by the operator of that car and adapted, when operated, to put the restoring mechanism in condition such that the selecting device 35 of the corresponding car will accomplish the restoration, said restoring mechanism also comprising means corresponding to each floor and coöperating with said selecting device, whereby the operator in the 40 car can restore only those push-button-set mechanisms corresponding to the floor where the car then is.

21. In an elevator signaling apparatus in

combination, a car, electrically-operated signaling means, means for operating the 45 same comprising a passenger's button at each floor and mechanism corresponding to each button and set thereby, restoring mechanism comprising a selecting device moved correspondingly with the car whereby the 50 restoring mechanism is adapted to restore all said passenger's button-set mechanisms in succession and correspondingly with the movement of the car, said restoring mechanism being normally incapable of accomplishing the restoration, and means controllable by the operator in the car and adapted, 55 when operated to put said restoring mechanism in condition such that the selecting device will accomplish the restoration. 60

22. In an elevator signaling apparatus in combination, a car, electrically-operated signaling means, means for operating the same comprising a passenger's-button at each floor and mechanism corresponding to each button and set thereby, restoring mechanism comprising a selecting device moved correspondingly with the car whereby the restoring mechanism is adapted to restore all 65 said passenger's-button-set mechanisms in 70 succession and correspondingly with the movement of the car, said restoring mechanism being normally incapable of accomplishing the restoration, and switch mechanism outside of and not carried by the car 75 and controllable by the operator in the car and adapted, when operated, to put said restoring mechanism in condition such that the selecting device will accomplish the restoration. 80
